UNITED STATES PATENT OFFICE.

JOHN GALLAGHER, OF BROOKLYN, NEW YORK, ASSIGNOR TO HIMSELF,
CHRISTOPHER DORFLINGER, ANSON JUDSON, AND ANTOINE REGAN,
ALL OF SAME PLACE.

IMPROVEMENT IN LIGHTING AND TRIMMING LAMPS.

Specification forming part of Letters Patent No. 35,733, dated June 24, 1862.

To all whom it may concern:

Be it known that I, JOHN GALLAGHER, of Brooklyn, in the county of Kings and State of New York, have invented an Improvement in Lamps for Burning Kerosene, Coal, or Similar Oils, of which the following is a specification.

The nature of my invention consists of an improvement in burners for lamps burning kerosene, coal, or similar oils, so as to obviate the necessity of removing or displacing the chimney in filling, trimming, or lighting the lamp.

A burner with my improvement may be constructed of a variety of forms externally; but I prefer constructing it as herein described, reference being had to the accompanying drawings, with letters of reference marked thereon, the red lines showing the positions of the parts when it is required to fill, trim, or light the lamp.

Figure 1 is a longitudinal elevation giving an external and also an internal view and vertical cross-section of the wick-tube. Fig. 2 is a longitudinal elevation of the same, showing the opening or door through which the lamp is filled, trimmed, and lighted. Fig. 3 shows a plan of the wick-tube with its appendages. Fig. 4 is an elevation of the same. Fig. 5 is the wick-tube and appendages in the different positions required for filling, trimming, or lighting the lamp.

A is the body or shell of the burner with my improvement, which I construct of a cylindrical form, and of a diameter and length suitable for the lamp for which it is intended.

The sides of the body A, I perforate to admit the proper supply of air to support combustion. On one side of the body A, and near the center longitudinally, I make an opening, B, sufficiently large to allow the wick-tube C to protrude. The opening B is fitted with a door or slide, D, which is also perforated the same as the body A, to which it is attached by a hinge or other suitable device. On opposite sides of the body A, at right angles with opening B, and on or near a line horizontal with the center of the opening B, are situated the

bearings E E, which support the wick-tube C, together with the disk or cover F. This disk or cover has attached to it two journals, I I, to correspond with and fit the bearings E E. In the body A one of the journals I terminates outside in a crank, G, to which is attached a spring pin or wrist, H, intended to keep the wick-tube C in a vertical or proper position by means of a corresponding opening or depression in the body A.

J is a cone or deflector, which has at its top or apex an opening of the ordinary form. Its base terminates in a flange in the ordinary way, and is supported by an internal projection in the body of the burner A. The cone J, together with the chimney Q, may be held down by any of the ordinary devices now in use for that purpose.

The body A is attached to the fount or body of the lamp R by means of a collar, O, either sliding over, or by means of a screw in the ordinary way.

In operating a burner of my improvement the door D is opened, the spring-pin H is withdrawn from the hole or depression in the body A, the crank is then depressed or turned to about one-fourth of a revolution. This causes the wick-tube C to protrude through the opening B sufficiently to admit of filling, trimming, or lighting the lamp without the necessity of removing or disturbing the chimney.

Having thus, I believe, fully described my invention, I now set forth my claims.

I claim as my invention and desire to secure by Letters Patent—

1. Suspending the wick-tube C by means of the journals I I, or their equivalents, and operating substantially as and for the purposes herein described.
2. The opening B, with its door D, for the purposes herein described and set forth.

JOHN GALLAGHER.
